DUPLEX PARKING METER HOUSING

Lester D. Sollenberger and Rodney J. Faxon, Chicago,
Ill., assignors to Miller Meters, Inc., a corporation of
Illinois

Application January 19, 1955, Serial No. 34,070

Term of patent 14 years

(Cl. D52—3)

Fig. 1.

Fig. 2.

Fig. 3.

*Fig. 4.**Fig. 5.**Fig. 6.*Fig. 1 is a front elevational view of a duplex parking meter housing showing our new design;

Fig. 2 is a side elevational view of the duplex parking meter housing of Fig. 1;

Fig. 3 is a top plan view of the duplex parking meter housing shown in Figs. 1 and 2;

Fig. 4 is a view like Fig. 1 showing the duplex parking meter housing in a different adjusted position;

Fig. 5 is a view like Fig. 2 showing the duplex parking meter housing in the adjusted position of Fig. 4; and

Fig. 6 is a view like Fig. 3 showing the duplex parking meter housing in the adjusted position of Figs. 4 and 5.

The appearance of the rear of the duplex parking meter housing, when in the position illustrated in Figs. 1-3,

is substantially the same as the front view seen in Fig. 1, and the appearance of the rear of the duplex parking meter housing in the adjusted position of Figs. 4-6 is substantially the same as the front seen in Fig. 4.

We claim:

The ornamental design for a duplex parking meter housing, as shown and described.
